Gerald L. Kitson, 9709 Belding Road,
Rockford, Mich. 49341

Continuation-in-part of design application Ser. No.
404,727, Oct. 9, 1973. This application June 20,
1974, Ser. No. 481,392

Term of patent 14 years

Int. Cl. D25—03

U.S. CL. D30—1

FIG. 1 is a perspective view of an A-frame housing for poultry cage systems showing my new design, an intermediate portion being broken away and omitted to indicate indeterminate length;

FIG. 2 is a reduced scale top plan view; and

FIG. 3 is a cross-sectional view taken along line 3—3 of FIG. 1.

This application is a continuation-in-part of my co-pending application Ser. No. 404,727, filed Oct. 9, 1973, entitled A-Frame Poultry Cage Shelter.

I claim:

The ornamental design for an A-frame housing for poultry cage systems, as shown and described.
